Primary Examiner — Rashida Johnson

CLAIM

I claim the ornamental design for a Mariachi suit, as shown and described.

DESCRIPTION

FIG. 1 is a front view of the jacket portion of a Mariachi suit showing my new design;

FIG. 2 is a rear view thereof;

FIG. 3 is a side view thereof;

FIG. 4 is a front view of the vest portion of the Mariachi suit;

FIG. 5 is a rear view thereof;

FIG. 6 is a side view thereof;

FIG. 7 is a front view of the pants portion of the Mariachi suit;

FIG. 8 is a rear view thereof;

FIG. 9 is a side view thereof;

FIG. 10 is a front view of the shirt portion of the Mariachi suit;

FIG. 11 is a rear view thereof;

FIG. 12 is a side view thereof;

FIG. 13 is a front view of the necktie portion of the Mariachi suit; the necktie shown folded; and,

FIG. 14 is another front view of the necktie portion shown unfolded.
